(57) **CLAIM**

The ornamental design for an inflatable seat for a child carrier, as shown and described.

DESCRIPTION

FIG. 1 is a front perspective view of the inflatable seat for a child carrier showing my new design;

FIG. 2 is a rear perspective view thereof;

FIG. 3 is a left side perspective view thereof;

FIG. 4 is a right side perspective view thereof;

FIG. 5 is a bottom perspective view thereof;

FIG. 6 is a top rear perspective view thereof;

FIG. 7 is a front right side perspective view thereof;

FIG. 8 is a rear right side perspective view thereof; and,

FIG. 9 is a front left side perspective view thereof.

Any shading and cross-hatching shown in the drawings are not features of the design, but are utilized to illustrate the surface contours of the inflatable seat design in the drawings.
